UNITED STATES PATENT OFFICE.

GUSTAV PFANNKUCHE, OF EXETER, NEW HAMPSHIRE, AND ALFRED PFANNKUCHE, OF CLEVELAND, OHIO, ASSIGNEES TO THE BRUSH ELECTRIC COMPANY, OF CLEVELAND, OHIO.

ELECTRIC CONVERTER.

SPECIFICATION forming part of Letters Patent No. 499,852, dated June 20, 1893.

Application filed May 13, 1887. Serial No. 238,084. (No model.)

To all whom it may concern:

Be it known that we, GUSTAV PFANNKUCHE, a resident of Exeter, Rockingham county, in the State of New Hampshire, and ALFRED PFANNKUCHE, a resident of Cleveland, in the State of Ohio, have invented certain new and useful Improvements in Electric Converters or Inductoriums, of which the following is a specification.

- 5 10 15 20 25 30 35 40 45 50
- This invention relates to inductoriums or induction coils and especially to those inductoriums which are employed for converting or translating a current of one character on a primary circuit into a current of another character on a secondary circuit. Inductoriums of this class are commonly known as electric "converters" or "transformers" or "transformators," or "inductive translators." They are chiefly employed in those systems of electric distribution wherein a current of high electro-motive force is transmitted to a distance over a line circuit which is connected to the primary wire of the converter, and a current of considerable density and volume and of low electro-motive force is induced in the secondary wire of the converter, which is connected with a local or secondary circuit in which are installed incandescent electric lamps or other devices for consuming electric energy. Such a system admits of the transmission of the electric energy to great distances over a small and consequently cheap conducting wire and with but little loss of potential, and enables a uniform current from one central generating station to be translated into currents of different characters at several different consuming stations, according to the varying wants of different subscribers or consumers. For the operation of such a system it is essential that the primary circuit be fed with a current the potential of which is subject to rapid and continual fluctuation. For this purpose alternating currents have been employed. Continuous currents have also been suggested, the requisite fluctuation to be obtained by rapidly interrupting the current after the manner of a rheotome, by means of a commutator. The latter method is impracticable on account of the heavy sparking which would result. The

former method has proved practicable but is nevertheless subject to certain disadvantages. A third method consists in the employment of intense pulsatory currents of continuous direction, or currents which are 55 subject to a rapid and continual rise and fall of potential without being reversed or alternated. This method, which possesses all the advantages of an alternating current and has in addition the properties and capabilities of 60 a continuous current, is fully disclosed in an application for a patent for "systems and apparatus for the production and distribution of electric energy" which we have executed and are about to file. For the operation of the improved converters which we are about to describe herein, we prefer to employ a pulsatory current of the character described in that application.

When an electric current is passing through 70 a wire the wire becomes surrounded by a tubular "field of force," that is, by magnetic lines of force which circle round the wire in a direction depending on the direction in which the current is passing through the wire. 75 These lines of force are commonly called the "magnetic whirl." The density of the field of force is greatest close to the wire and decreases in proportion to the square of the distance from the current. If a second wire is 80 brought into close proximity with the excited wire so that the lines of force circling round the latter shall cut the second wire, a momentary current will be induced therein in the opposite direction to the current in the first 85 wire. Or, in the case of two parallel wires in close proximity the establishing of a current in one wire, or a rise of potential in a current already established therein, will induce a momentary current in the opposite direction in 90 the other wire. Inversely, the cessation of the current, or a fall in the potential of the current, in the primary wire will induce in the secondary wire another momentary current of the same direction as the primary current but of opposite direction to the first secondary current. A reversal of the primary current will produce the same effect in the secondary wire. Thus, whenever the potential of the primary current is either rising or 95 100

falling, either entirely on one side of what we may term the zero line (as in a pulsatory current) or from one side to the other thereof (as in an alternating current), there results a secondary current which flows in one direction during a rising positive (or falling negative) potential, and in the opposite direction during a falling positive (or rising negative) potential.

In order to get the best inductive effect from the magnetic whirls around the primary wire it is necessary to bring the secondary wire into the densest portion of the field of force, or in other words, to bring it as close as possible to the primary wire. To this end, in the construction of our improved converter we make the secondary conductor in the form of a tube and draw it closely over a well insulated primary conducting wire. Thus the conducting cross-section of the secondary conductor occupies necessarily,—with the exception of the thickness of the insulating material,—the densest portion of the field of force. This arrangement may also be reversed—that is to say the primary conductor may be made in the form of a tube with the secondary conductor placed inside of it.

In order to most economically utilize the field of force generated in the primary conductor; it is necessary to prevent the wasting or scattering of the lines of force, and to so concentrate them that they shall act most effectively on the secondary conductor. To this end the employment of a mass of magnetic material, such as soft iron, is useful, and many methods have been proposed for accomplishing this result, such for instance as winding the primary and secondary wires on an iron core, the ends of the latter being preferably united to form a closed magnetic circuit; and such also as winding upon a coil of the primary and secondary wire an outer covering or envelope of soft iron wire. According to our invention we accomplish this object by inclosing the primary and secondary inductors in a magnetic field of tubular form, such as a soft iron tube or pipe.

According to a further improvement introduced by our present invention we utilize the magnetic tubular shield as the secondary conductor. To this end we draw a well insulated copper wire or other suitable primary conductor into the bore of an iron tube, the latter being made of sufficient diameter to afford the requisite conductivity for the secondary current. Furthermore in order to generate in the secondary conductor a current of sufficient density we employ two or more primary conductors connected in series and pass them together through the tubular secondary conductor, whereby the density of the secondary current is as much greater than would be induced by the current through a single primary conductor as is the product of such density multiplied by the number of primary conductors so employed.

Our invention provides an electric con-

verter or inductorium embodying the features which we have thus far described with also other features of construction by which it may be rendered applicable to a great variety of conditions, both electrical and mechanical.

We will now proceed to describe our invention in detail with reference to the accompanying drawings, wherein—

Figure 1 includes a transverse section and a partially dissected side view of one construction of inductive conductors according to our invention. Figs. 2, 3, 4, 5, 6, 7 and 8 are similar sectional and side views showing other constructions. Fig. 9 is a transverse section showing a modified construction. Fig. 10 includes a section and dissected side view of another modified construction. Fig. 11 is a perspective view partially dissected showing another modification. Fig. 12 is a transverse section of a modification of the construction shown in Fig. 11. Figs. 13, 14 and 15 are transverse sections of still other modifications. Fig. 16 is a diagrammatic view partially in perspective illustrating a simple arrangement of circuit connection. Fig. 17 is a perspective view illustrating one method of applying our invention in connection with a building and air line wires. Fig. 18 is a diagram pertaining to the construction shown in Fig. 16. Fig. 19 is a side elevation of an inductive battery constructed according to our invention. Fig. 20 is a plan thereof partly in horizontal section. Fig. 21 is an elevation showing a detail of the said battery; and Fig. 22 is a transverse section of Fig. 21 cut on the line 22—22.

In the several figures wherein cross-sections of the conductors are shown the primary conductors are drawn in solid black while the secondary conductors are tinted with section shading.

Fig. 1 shows a copper wire *a* inclosed in an insulation *i* around which is drawn a copper tube *b*. The wire *a* is the primary conductor and the wire *b* the secondary. Around the latter are indicated some of the lines of force of the magnetic whirl due to the primary current. (The lines of force due to the secondary current are not shown.) It is obvious that with a secondary conductor of tubular form drawn closely around the primary conductor, the densest portion of the field of force that it is possible to reach is occupied by the secondary conductor, so that the maximum inductive effect is necessarily realized. Compound conductors of this construction may be made by taking a well insulated copper wire and drawing the copper tube over it in similar manner to that heretofore employed for manufacturing lead-covered cables. The exterior of the copper tube *b* may be covered with an insulating wrapping if desired.

With the construction just described only a portion of the lines of force would be utilized for inductive work. We therefore in order to concentrate the lines of force and form a magnetic closed circuit around the conduct-

ors inclose the latter in a magnetic envelope or sheath. This may be done in various ways some examples of which we have shown.

Fig. 2 shows the conductors constructed as in Fig. 1 with the addition of a tube *d* of soft iron within which the conductors *a* *b* are placed, a layer of insulating material being formed around the conductor *b* to keep it from contact with the iron tube. The iron tube *d* may be slotted longitudinally, as shown at *c*, if desired.

Fig. 3 shows another construction of the external magnetic envelope *d* the latter being formed by winding one, two or more layers of soft iron wire around the insulation on the conductor *b*.

Fig. 4 shows still another construction of the magnetic sheath. A number of washers *ff* of soft iron are slipped over the outer conductor, which has been previously insulated, and are laid together face to face in such manner as to form a continuous tube *d*. The respective washers may advantageously be slightly separated or insulated from one another by being varnished or by having tissue paper or other insulating material interleaved with them. Such separation acts to prevent the formation of Foucault currents in the magnetic envelope, since such currents tend to assume a longitudinal direction, flowing in one direction along the inner portion of the iron sheath and in the opposite direction along the outer portion thereof. In the construction shown in Fig. 3 the suppression of Foucault currents may also be readily effected by slightly insulating the convolutions of iron wire of which the magnetic envelope is formed.

Fig. 5 shows a reversal of the conductors *a* and *b*, the former now being employed as the secondary conductor and the latter as the primary conductor. This arrangement however we do not consider so effective as that first described since the secondary conductor, being inclosed within the primary, is acted upon by lines of force circulating inside of the primary and consequently in the opposite direction to the lines of force outside of the primary, so that to some extent the two sets of lines of force neutralize each other.

Fig. 6 shows a construction wherein a copper primary wire *a* surrounded by insulation *i* is inclosed within a secondary tubular conductor *b d* of soft iron or other magnetic material, which serves not only as the secondary conductor *b* but also performs the function of the magnetic envelope or sheath *d* already described. Thus the construction of the inductive conductors is considerably simplified and cheapened without the loss of any of the advantages inherent in the constructions previously described. In view of the well known fact that the electric conductivity of iron is greatly inferior to that of copper, we construct the iron conductor *b d* of an area of cross-section enough greater than that which would be given to a copper conductor to attain the same conductivity. For ordinary ap-

plications, wherein such conversion of current is desired as is suitable for operating incandescent lamps in multiple arc in the secondary circuit, the proportion thus necessarily given to the iron tube *b d* is such as is most suitable for the magnetic envelope. In this construction the generation of Foucault currents in the magnetic envelope is of no consequence, since the opposite ends of the magnetic envelope are connected in the secondary circuit, so that the currents thus induced are closed through the circuit and are not forced to eddy within the iron sheath and thereby to waste energy by heating the iron, but are utilized as the secondary currents of the inductorium. The iron tube *b d* may be slotted longitudinally in the same manner as is shown in Fig. 2, if desired.

The pair of single primary and secondary conductors shown in Fig. 6 will, with a given primary current, generate a secondary current of given density. If the density of the secondary current is desired to be greater than that thus afforded, this may be accomplished by inclosing two, three or more primary wires within the one secondary conductor. This construction is shown in Fig. 7 where seven primary wires are shown grouped together and inclosed within the one tubular secondary conductor *b d*. The primary wires should be connected in series so that the same current will traverse one after another in succession and all in the same direction. Thus, as it were, seven distinct induced currents are superposed one upon another in the secondary conductor, all being of the same potential, so that the secondary current is given seven times the density or volume that would result from the employment of a single primary wire. Inductive conductors of this character may be constructed in various ways. The primary wire or group of primary wires may be drawn into the bore of an iron pipe, their ends being left protruding at both ends of the iron pipe in order that the requisite connections may be made. Or the iron pipe may be constructed in two parts diametrically divided in longitudinal direction as indicated in Fig. 8, in which case the two halves will be placed together with the primary wire or wires between them and will be fastened by an occasional winding or tying of wire or other material or by an exterior wrapping of insulating material, the latter method being the one shown in Fig. 8 at *l*. The two halves of the tubular conductor *b d* may be in contact with each other or they may be separated by a layer of insulating material, in which latter case they may be connected to the secondary circuit in series instead of in multiple arc, or one part may be connected in one secondary circuit and the other part in another secondary circuit. The tubular conductor *b d* may be still further sub-divided if desired, into three, four or more parts of equal or unequal area of cross-section. Fig. 9 shows a construction wherein

the external conductor is formed of four longitudinal sections. These sections may be insulated from one another and connected together in series, or connected in different 5 secondary circuits, or they may be insulated or uninsulated and all connected in multiple are as may be preferred.

Fig. 10 shows a sub-division of the secondary conductor *b* which here consists of a 10 number of iron wires arranged parallel to the primary wires and completely inclosing them, the whole being bound together by an external winding, as before described. These iron wires may be naked so that they shall all 15 constitute practically one conductor, or they may be more or less insulated from one another and connected either in series or multiple, or according to some intermediate arrangement.

20 In case the secondary conductor consists of an iron tube or of a tubular arrangement of rigid sections it is preferable to make the conductors straight, as shown in Figs. 1 to 10; but when iron wires are employed for the external conductor it may be advantageous to construct the device in annular form. Fig. 11 shows such a construction. In this figure a single primary conductor *a* is wound into a coil of seven (more or less) convolutions and 25 the inclosing secondary conductor consists of an iron wire *b* suitably insulated and wound around parallel with the primary wire and in such manner as to inclose it on all sides, as clearly shown. With the proportions shown 30 in this figure the induced secondary currents will be of considerable intensity, but if a secondary current of low potential and great density is required this may be readily attained by winding a number of iron wires together 35 and connecting their ends to the secondary circuit in multiple arc, as will be well understood. The entire coil is bound together at intervals by wrappings of wire, shown at *h h*. A coil thus constructed fully complies with 40 the condition of our invention in that the secondary conductor is substantially a tube inclosing the primary, and in that the external magnetic envelope by means of which the 45 magnetic lines of force are given a closed 50 short circuit of low resistance serves also as the secondary conductor.

Fig. 12 is a cross-section of a coil similar to that shown in Fig. 11 but wherein the construction is inverted in that the iron secondary 55 wires *b* are wound as a central core and the primary wires *a* are laid against the exterior of this core and confined thereto by wrappings at intervals.

It is not essential to our invention that the 60 primary conductor be round or of circular cross-section, nor that the secondary conductor shall be a round tube or in fact that it shall be a complete tube at all, since various modifications of both may be readily devised 65 which shall come within the proper scope of our invention. Fig. 13 illustrates one example of such a modification. In this figure

the primary conductor *a* consists of a flat copper strip or ribbon, covered with an insulating coating *i*, and the secondary conductor *b* 70 consists of a strip of copper or soft iron, preferably the latter, which is bent around the two opposite sides of the copper strip *a* thereby almost entirely inclosing the latter. The extreme edges of the conductor *b* may be 75 pressed together or not as desired. Fig. 14 shows a similar construction with the addition of a second flat strip bent around the strip *b* and having its edges brought together or nearly so. In this case the inner folded strip *b* may be 80 the secondary conductor and may be constructed of copper and the outer folded strip *d* may be of iron and constitute the magnetic envelope; or both may be of iron and constitute together the secondary conductor; or in the 85 latter case they may be insulated from each other and connected to the secondary circuit in series or each may be connected in a separate secondary circuit. Fig. 15 shows still another construction wherein the external conductor 90 is not in fact a tube at all but is made of two strips of iron laid against opposite sides of the primary conducting strip or ribbon *a* and fastened together by a suitable external winding or otherwise. 95

Having thus described a great variety of constructions of inductive conductors according to our invention we will now proceed to describe some methods of coupling or connecting them in such manner as to render them conveniently applicable for practical use.

Fig. 16 shows one method of applying our invention. A A are the parallel conductors of the main or line circuit and B B are two 105 of our compound inductive conductors of the construction illustrated in Fig. 7 or Fig. 8. The primary wire *a* leads from one of the line wires A, passes through the iron tube *b* of one of the conductors B, passes back through 110 the iron tube of the other conductor, then again through the first, again back to the second and so on as many times as may be desired, and finally joins the other conductor A of the main line. Thus the primary wire 115 forms a shunt or multiple arc between the two wires of the main circuit, and the several primary wires inclosed in each of the iron tubes *b* are traversed by the same shunted or divided current in succession or serially. 120 The connections are made by constructing the compound conductors with their primary wires protruding at the ends so that they may be connected together by twisting or coupling the ends of the respective wires to the 125 same effect as though one unbroken wire were passed back and forth through the two tubes as just described. The tubes *b* are electrically connected together at one end, as shown at the left hand in Fig. 16, and their 130 opposite or right hand ends are connected to the leading-off wires of the secondary circuit. These connections may readily be made by the same devices by which the tubes are fas-

tened in position, as shown in Fig. 16. The connection at the left hand ends of the tube consists of a pair of clamps *c c* embracing the opposite sides of the tube and drawn together by a screw or bolt *k* which may also serve to fasten them to the wall or other part which is to support the conductor. The connections at the right hand end of the tube are made by means of clamps or clips *m m* which are fastened to the wall, &c., by screws *k'*. The clamps *c c* and *m m* are of metal and are brought into close metallic contact with the surfaces of the tubes.

An inductive converter of the construction just described may be of any desired proportions and may be mounted or arranged in various ways according to the taste or desires of the consumer, or the circumstances under which the connections have to be made. Fig. 17 shows one suitable arrangement. The inductive converter is here applied by fastening it against the front wall of a building, as clearly shown. This arrangement admits of convenience in the connection of the primary terminals with the wires *A A* of the line circuit, when the latter are carried through the streets on poles.

b b are the wires of the secondary circuit leading into the building. The converter tubes will be less conspicuous than in the illustrations, since they are there exaggerated in size in order to show them more clearly. They may be further concealed, if desired, by building them into the cornice or disposing them in any other manner that will suit the convenience of the architect or builder.

It may be desirable to so connect the iron tubes *b d* that they shall constitute practically a closed magnetic circuit, although we do not consider this necessary. If desired it may be accomplished in the manner shown in Fig. 18 which is a diagram showing only the iron tubes and their connections. At one end the tubes are connected together by a solid piece or block of iron *C*, and at the other end they are magnetically connected but electrically insulated by two iron blocks *C' C'* which approach each other but are maintained very slightly separated by leaving a narrow air space or by placing a sheet of thin mica or other insulating material between them. Thus the magnetic circuit is scarcely interrupted while electric short circuiting between the tubes is prevented.

The number of compound conductors *B B* that are connected together may be multiplied to any desired extent and the connections of the primary and secondary conductors may be according to any desired system, either series or multiple or any intermediate arrangement. We propose to combine them into what we may call inductive batteries consisting of a greater or less number of the compound conductors or inductive elements *B B*, according to circumstances.

We prefer to construct the compound conductors *B B* of standard lengths and dimen-

sions, the proportions being such that with a given uniform electro-motive force for the primary current with which they are to be used they will develop a certain standard electro-motive force or potential in the secondary conductor. For example, they may be made to give a difference or potential at the opposite terminals of the secondary conductor of, say one volt or two volts. Compound conductors thus uniformly proportioned we will herein-after refer to as standard inductive elements.

In order to build up an inductive battery we take a suitable number of such standard elements, which being constructed in the form of straight rods, we arrange side by side, leaving a little air space between them, and place them in a suitable frame or rack, made preferably of wood, and having thus secured them in place we couple together the opposite ends of the primary and secondary conductors according to any desired electrical arrangement.

Figs. 19 and 20 illustrate such a battery. The battery here shown consists of seventy-five elements *B B* each of one volt potential, with their secondaries coupled together in series in order to deliver a current to the secondary circuit having an electro-motive force of seventy-five volts. There are five rows of elements with fifteen elements in each row. They are held in place by being clamped at their upper and lower ends between notched bars *n n* which are drawn together by screw bolts *p p* passing through the bars at intervals. The ends of the bars *n n* are confined in grooves *q q* in vertical end frames *D D*, which are drawn together by screw rods *r r* in order to make the whole structure firm. The end frames *D D* are mounted on a base plate *E*. The primary binding posts *p' p'* are connected with the line conductors *A A* by wires *a' a'* and with the primary wires *a a* in the elements *B B* by means of wires *a'' a''*, and the primary wires are connected together from one element to another by connections *t t*. The terminals of the secondary circuit *S* are connected to binding-posts *s s* which are joined by wires *b' b'* to the secondary conductors *b b* of the first and last elements *B B* of the series, and the secondary conductors are connected together from one element to another by connections *v v*. For the sake of simplicity we have illustrated in these figures the construction of compound conductor or inductive element *B* shown in Fig. 6, wherein only a single primary wire is inclosed in the secondary tube.

Fig. 21 shows the preferred method of connecting together the terminals of the respective primary and secondary conductors of adjoining elements. The primary wire *a* of each element protrudes beyond the secondary tubes *b d*, and a coupling or bridge *t* is slipped upon their projecting ends. The terminals of the secondary tube are connected by means of a clamp *v* drawn together by a screw *u* as shown in Figs. 21 and 22.

The inductive converters provided by our

present invention possess the important advantages of a high inductive efficiency, cheapness and ease of manufacture, simplicity of construction, interchangeability of parts, and great adaptability to different conditions by the facility with which the conductors may be coupled in different arrangements, and the potential in the secondary conductor may be increased or diminished at will. By our construction of an inductive battery it is easy to add a few elements or to take out a few, either permanently or temporarily; for the latter purpose the couplings may be shifted by hand or the connections may be changed by means of a switch or commutator. In this way the battery may be adapted to any possible difference of potential that may exist in different portions of long main circuits; or variations of potential occurring from time to time may be compensated for.

What we claim as our invention, and desire to secure by Letters Patent, is, in inducto-riums or inductive converters, the following defined novel features and combinations, substantially as hereinbefore specified, namely:

1. In an electric converter the combination of a primary conductor with a secondary conductor of magnetic material arranged to inclose or nearly inclose the primary, whereby it constitutes a magnetic envelope for the lines of force.
2. In an electric converter the combination of a primary conductor with a tubular secondary conductor of magnetic material arranged to inclose the primary, whereby it constitutes a magnetic envelope or closed circuit for the lines of force.
3. In an electric converter the combination of a primary conductor with a secondary conductor of magnetic material constructed to inclose the primary and constitute a magnetic envelope for the lines of force, and subdivided longitudinally into two or more sections.
4. In an electric converter the combination of a primary conductor with a secondary conductor of magnetic material constructed to inclose the primary and constitute a magnetic envelope for the lines of force, and subdivided longitudinally into two or more sections, with insulating material intervening between the sections, whereby the latter may constitute distinct conductors.

5. In an electric converter the combination of a primary conductor with a secondary conductor consisting of an iron tube inclosing the primary conductor. 55

6. In an electric converter the combination of a tubular secondary conductor of magnetic material with two or more primary conductors 60 passing through it and insulated from one another.

7. In an electric converter the combination of two or more tubular secondary conductors of magnetic material with two or more primary conductors passing through them and connected in series, whereby the primary current passes within each secondary conductor two or more times in the same direction. 65

8. In an electric converter battery the combination of a number of inductive elements, each consisting of a primary and secondary conductor laid parallel, the several elements arranged parallel with one another in the same plane, with notched bars engaging said elements between them and with clamping screws engaging said bars and adapted to draw them together to clamp the elements between them. 70

9. In an electric converter battery the combination of a number of inductive elements, each consisting of a primary and secondary conductor laid parallel, the several elements arranged parallel with one another in sets the elements of each set being disposed in the same plane and the several sets of elements being arranged in approximately parallel planes, with a clamping frame consisting of bars arranged on opposite sides of the elements of each set and between the respective sets of elements, and clamping screws for drawing said bars together and thereby clamping the several elements between them. 75 80
